CABINET CONSTRUCTION

Francis John Osuch, Grosse Pointe, Mich., assignor to Robot Products Corporation, Detroit, Mich., a corporation of Michigan

Application August 24, 1938, Serial No. 226,531

3 Claims. (Cl. 312—112)

This invention relates to cabinets, and more particularly to storage cabinets of the type used in the kitchen and the like.

The present application is a continuation in part of my co-pending application Serial Number 70,744, filed March 25, 1936, for Cabinet construction.

In the manufacture of storage cabinets and the like having more than one compartment to be assembled upon delivery to the user, some means should be provided to compensate for manufacturing irregularities so that the various sections of the unit may be readily secured together without fabrication at the point of use.

This is particularly true when the cabinet structure is made of steel with a coat of vitreous enamel which is easily chipped or marred should the entire unit be assembled with bolts and screws to force the various sections into position instead of having provisions for adjusting to compensate for the manufacturing irregularities. Accordingly, it is one of the objects of my invention to provide a unitary structure which may be readily assembled at the point of use without in any manner chipping or marring the enamel of the cabinet.

Another object of my invention is to provide a unitary shelving structure consisting of a plurality of superimposed compartments having open fronts and in which one compartment is of less depth than the compartment thereabove so as to dispose the compartment in stepped arrangement downwardly and rearwardly.

Another object of my invention is to provide a unitary cabinet structure consisting of numerous storage compartments manufactured in sections and which may be readily assembled as a unit, and to arrange certain parts of the structure so that the same may be adjustable to compensate for manufacturing irregularities to thus permit the ready assembly of the unit.

Another object of my invention is to provide a storage cabinet including the shelf supporting section and end sections, and to arrange the shelf supporting section in such a manner that it is telescoped within the end sections so that the entire structure is expandable or contractible to fit in a given wall space.

Another object of my invention is to provide the sections of the aforementioned unit with adjustable portions so as to permit interchangeability of sections in the unit.

Other objects and advantages will be apparent from the following description and accompanying drawings, wherein a preferred form of the present invention is clearly shown.

In the drawings:

Fig. 1 is a front view in elevation of the unit embodying features of my invention;

Fig. 2 is a top view of the unit shown in Fig. 1;

Fig. 3 is a fragmentary view taken along the line 3—3 of Fig. 1;

Fig. 4 is a fragmentary view taken in the direction of arrows 4—4 of Fig. 1;

Fig. 5 is a view of a modified form of embodiment of my invention;

Fig. 6 is a fragmentary view in a further modified form disclosing my invention;

Fig. 7 is a front view in elevation of a modified form of unit embodying features of my invention;

Fig. 8 is a view taken in the direction of arrows 8—8 of Fig. 7;

Fig. 9 is a view taken in the direction of arrows 9—9 of Fig. 7;

Fig. 10 is an enlarged fragmentary view of the upper left hand corner of the structure shown in Fig. 7;

Fig. 11 is an enlarged fragmentary view of the lower left hand corner of the structure shown in Fig. 7;

Fig. 12 is an enlarged fragmentary view of the upper left hand corner of the structure shown in Fig. 8; and

Fig. 13 is a fragmentary view of the lower part of the structure shown in Fig. 8 and shown in modified form.

Referring to the drawings, the numeral 20 designates, in general, a unitary structure embodying features of my invention. Unit 20 includes a cabinet sink 21, cabinet 23, which is adapted to house an electric ironer (not shown), refrigerator cabinet 25, storage cabinet 26, storage cabinet 27 and storage cabinet 28. The cabinets 21, 23, 25, 26, 27 and 28 may be secured together by any suitable means, such as bolts, screws and the like.

As will be noted in the drawings, the cabinets 27 and 28 form a unitary upright structure, and the refrigerator cabinet 25 and storage cabinet 26 form an upright structure which is spaced apart from the storage cabinets 27 and 28. Between these two upright structures, there is provided shelf supporting structures 30. The structures 30 provide three shelf members 32, 33 and 34 vertically spaced with the shelf 32 extending forwardly from the rear of the cabinet further than shelf 33 or 34, and the shelf member 32 extending forwardly from the rear of the cabinet further than the shelf 34. The shelf members 32 are closed at their forward ends by swinging doors 35.

36, preferably secured to the shelf 32 by hinges 38. As will be noted in Fig. 3, the shelf structure 32 extends laterally beyond the doors 36 where it cooperates with end section 40 in telescopic arrangement. Preferably, the end section 40 is rigidly secured to the section 28 in any suitable manner. In order to maintain the shelf structure 32 permanently in position, the end section 40 is adapted to frictionally engage the end portion of the shelf structure 32 so as to clamp the shelf section in position but to permit relative movement between end section 40 and the shelf 32 when it is desired to effect movement therebetween.

15 By having the shelf members 32, 33 and 34 of different widths as disclosed it is possible to mount the structure 30 above and below the height of the average person without having any part of the structure in the way of the user thereof as is the case in the use of conventional shelf structure. This is occasioned because the uppermost shelf may be above the user's head while the lower shelves retreat away from the user. This type of structure is particularly advantageous 25 where it is desired to place a work table or sink below such shelf structure as the shelf structure does not interfere with the work on the sink or work table, nor do the lower shelves extend outwardly far enough to hide the work from view 30 when the housekeeper or user is standing up.

The rear of the cabinet is closed by rear panel 44 which is secured to cabinet structure 28 and cabinet structure 26 by screws 46. Preferably, the screws extend through elongated slots 48 in the member 44 so as to permit adjustment of the member 44 relative to the rear of the cabinet. On the opposite end of the shelf structure 32, there is provided an end section 50 which corresponds to the end section 40, the end section 50 being rigidly secured to the end section 52 of a shelf structure 54. The shelf structure 54 corresponds in all respects to shelf structure 32. The shelf structure 32 is also arranged to telescope within the end section 50 and is frictionally engaged thereby so as to permit relative movement between the two surfaces. A trim element 56 is provided to overlap the joint between the sections 40-50 and the shelf structure 32. The trim section includes a flat portion 58 which is preferably secured to the end section 40 and an inwardly directed flange 60 which is adapted to engage shelf structure 32 so as to effect a seal joint therebetween.

From the foregoing it will be noted that the stepped shelf structure 30 is adjustable in length 55 due to the arrangement between the various shelf structures and the end sections 40 and 50. By this arrangement there can be a variation of several inches in the entire width of the unit as manufactured at the factory, and upon setting up the job at the point of use the shelf structure may be expanded or contracted to take care of the several inch discrepancy in measurements. Furthermore, the rear panel of the cabinet, due to elongated slots 48, is arranged to take care of the variations in the over all width of the cabinet. Furthermore, some users may find it desirable to substitute for the ironer cabinet 23 an electric range or the like, and if so, there is likely to be 60 considerable difference in the width of the cabinet, thus necessitating an adjustment of certain parts of the cabinet to compensate for the difference in widths over the range and ironer. By making the shelf structures 30 and rear panel 65 adjustable with respect to the remaining parts

of the cabinet, it is possible to substitute various types of sections for those disclosed in the unit and at the same time compensate for any variations in width of the entire unit.

In Fig. 5 I have shown a modified form of shelf structure 70 which is adapted to be received within end section 72 in telescopic arrangement. However, in this section a trim element 74 is provided with an inwardly formed portion 76 which is adapted to frictionally engage the shelf structure 70 to clamp the shelf structure to the end section 72 but to permit relative movement therebetween when so desired. As shown, the structure 70 is slightly bent to aid in the frictional engagement with the portion 76.

Fig. 6 discloses a cup-shaped end member 80 adapted to close the end of shelf structure 82 with the shelf structure 82 being received by the cup-shaped end member 80 in telescopic arrangement. In some instances, it has been found desirable to manufacture merely the stepped shelf structure having end sections as shown at 80 independent of the entire unit 20. When structures of this type are manufactured independently of unit 20, it has been found desirable to 25 arrange the end sections 80 so that the same may be slid relative to the shelf structure 82 so as to vary the overall width of the cabinet to accommodate a given wall space. The joint between the end section 80 and the shelf structure 82 is covered by metal trim section 84 which is similar to the trim section 58 shown in Fig. 3.

In some instances it is unnecessary to have the stepped shelf structure made with adjustable ends. One instance is where it is desired to place a work table therebelow instead of sinks and ranges. In this case the work table and shelf structure may be made to definite dimensions at the factory. Another instance is in the low cost housing field where wall space is standardized. In this case the wall space dimensions are known and the shelf structure is made to definite dimensions at the factory. A third instance is where a work table of standard dimensions is placed below the shelf structure and sinks and ranges fitted to the work table at installation at point of use.

Referring to Figs. 7 to 12, there is shown a cabinet designated in general by the numeral 120. The cabinet 120 corresponds in all respects to 50 cabinet 20, with the exception of the stepped shelf arrangement. Also, the sink 21 and range 23 may be omitted, if desired, and a work table substituted. The cabinet 120 includes a refrigerator 125 and cabinets 126, 127, 128 and 130. The refrigerator 125 and cabinets 126, 127 and 128 correspond in all respects to refrigerator 25 and cabinets 26, 27 and 28, respectively.

Shelf structure cabinet 130 is somewhat different from shelf structure cabinet 30 and includes 60 top wall 140, bottom wall 144 and cup-shaped end walls 150. These walls are all preferably constructed of sheet metal. The top wall 140 is disposed on a horizontal plane and is provided with downturned edges 154 at the front and rear of the 65 cabinet. The top wall 140 also includes extension members 156 at the ends thereof. The extensions are formed on a slightly lower plane than the wall proper and are used for receiving and securing the cup-shaped end members 150 in a 70 manner about to be described. The bottom wall 144 includes a vertical section 162 and horizontal sections 164 and 166. The sections 164 and 166 are integrally formed with the section 162 and arranged so that section 164 is on a higher verti- 75

cal plane than section 166 and so that section 164 extends forwardly from section 162 and section 165 extends rearwardly from section 162. Bottom wall 162 is provided with an upturned edge 170 at the front of the cabinet and an upturned edge 172 at the rear of the cabinet. The rear of the cabinet may be closed by a rear member 175 which may be secured to edges 154 and 172 by welding or bolts (not shown). The front 10 of the cabinet includes mullions 178. The mullions include extensions 180 and 182 which are secured to edges 154 and 170, respectively, by welding or bolts (not shown). As shown in Fig. 11, the bottom wall 144 is provided with extensions 185 for receiving and securing the cup-shaped end members 150. The end members 150 are cup-shaped and include inwardly directed flanges 188 which are placed over extensions 156 of top wall 140 and extensions 185 of bottom wall 20 162. The end walls and extensions 156 and 185 are secured together preferably by welding or bolts (not shown). Edges 154 and 162 of walls 140 and 144 terminate in abutting relation to flanges 188 of end members 150.

25 Shelves 200 and 202 may be provided and these shelves may be carried by the end walls by brackets 204 and 206, respectively.

In Fig. 9 I have, for the purpose of clarity, omitted the shelves so as to better disclose the 30 bottom wall structure.

The front part of the cabinet is provided with openings 208 between the door mullions and also openings 210 provided in section 162 of wall structure 144. Openings 208 are closed by doors 35 212. Doors 212 are hinged to mullions 178 by hinges 220. The hinges may be welded or bolted to the mullions and doors. Doors 212 move above a vertical axis. The opening 210 in section 162 of wall structure 144 is closed by doors 225. 40 Doors 225 are hinged to section 162 by hinges 228. Hinges 228 may be welded or bolted to doors 225 and section 162. Doors 225 are the type which may be lifted up to move about a horizontal axis.

45 By the present arrangement there is provided a series of superimposed compartments 230 and 232 in which one compartment 232 is of less depth than the compartment 230 thereabove so as to dispose the compartments in stepped arrangement downwardly and rearwardly.

If desired, hinges 228 may be omitted from doors 225 and hangers (not shown) of the type used in conventional book shelves substituted for the hinges 228. In this case the front part of 55 the doors may be lifted upwardly and then the doors slid rearwardly into compartment 232.

In securing the cabinet together by welding as described it may be desirable to spot weld the various sheets of metal together. By providing the cup-shaped end members 150 and spot welding the end members to the extensions 156 and 185, a rigid structure without the use of panels and the like is provided. Also, by providing extensions 180 and 182 to door mullions 60 178 and spot welding such extensions to the top and bottom walls of the structure additional rigidity to the structure is provided.

Fig. 13 discloses an arrangement wherein compartment 232 is closed by a drawer front 250 instead of doors 225. A drawer 252 is secured to front 250. Since the compartment 232 may be

advantageously used for storing small articles, it may be in some instances desirable to use drawer 252 and front 250 instead of the open compartment closed by doors 225 as shown in Figs. 7 and 8.

If desired, the cabinet shelf structure 130 may be used independently of the remainder of the cabinet. Also, if desired, the cabinet shelf structure may be mounted directly to a wall of the room where it is to be used with the rear panel 10 175 omitted.

Although only a preferred form of the invention has been illustrated and that form described in detail, it will be apparent to those skilled in the art that various modifications may 15 be made therein without departing from the spirit of the invention or from the scope of the appended claims.

I claim:

1. A wall cabinet comprising a unitary shelving structure having open ends and an upper portion of greater depth from front to rear than its lower portion and including a series of superimposed compartments having open fronts and in which one compartment is of less depth than 20 the compartment thereabove, so as to dispose the compartments in stepped arrangement downwardly and rearwardly, doors for the open fronts of the compartments hinged to fixed portions thereof and end members conforming to the contour of the shelving structure and each comprising an end wall having inwardly directed peripheral flanges embracing telescopically end portions of said structure, whereby the length of 25 30 35 the cabinet may be varied.

2. A wall cabinet comprising a unitary shelving structure having open ends and an upper portion of greater depth from front to rear than its lower portion and including a plurality of superimposed compartments having open fronts and in 40 which one compartment is of less depth than the compartment thereabove, so as to dispose the compartments in stepped arrangement downwardly and rearwardly, doors for the open fronts of the compartments 45 movably secured to fixed portions thereof and end members conforming to the contour of the shelving structure and each comprising an end wall having inwardly directed peripheral flanges embracing telescopically end portions of said 50 structure.

3. A wall cabinet comprising a unitary shelving structure having open ends and an upper portion of greater depth from front to rear than its lower portion and including a plurality of 55 superimposed compartments having open fronts and in which one compartment is of less depth than the compartment thereabove, so as to dispose the compartments in stepped arrangement downwardly and rearwardly, doors for each of the open fronts of the compartments 60 movably secured to fixed portions thereof and end members conforming to the contour of the shelving structure and each comprising an end wall having inwardly directed peripheral flanges 65 embracing end portions of said structure, with at least one of said flanges embracing telescopically an end portion of said structure whereby the length of the cabinet may be varied.

FRANCIS JOHN OSUCH. 70
